TOY AEROPLANE

Etienne Marcus, Paris, France

Application March 8, 1934, Serial No. 714,691
In France March 11, 1933

5 Claims. (Cl. 46—50)

It has heretofore been known to produce books comprising sheets of paper, which are generally coloured, from which a child can make, by cutting and folding, thus developing manual dexterity and constructive ability, small articles which reproduce, on a reduced scale, models of other existing objects.

This invention relates to the construction, in this manner, of gliding aeroplanes faithfully reproducing the types employed in civil and military aviation.

The said invention is characterized by various simple devices for assembling the parts, which can be employed singly or in combination in the same model.

The following description, illustrated by the accompanying drawings, shows, by way of example, some of the methods whereby the invention can be carried out.

20 Figures 1, 2, 3, 4 and 5 show outlines which may be printed on a sheet of paper or the like, and

Figures 6, 7, and 8 show a toy monoplane built of parts cut from a sheet thus marked.

25 Figures 9, 10, 11 and 12 illustrate a modification of the manner of inserting the wing.

Figure 13 is a side view of a toy biplane.

The outlines marked on a sheet, as shown in Figures 1, 2, 3, 4 and 5 represent the following parts: In Figure 1, 1 is the body or fuselage 30 which is slit at 2, 3, 4, 5, 6 and 6a, with parts 7, 8 representing wheels. The rudder controlling elevation is shown at 9, two lateral bands at 10 and 11 to serve as balance weights and two tongues 12 and 13 for attaching together the

35 parts. Figure 2 shows the supporting wings with the outline of two teeth or filling pieces 14, 15 and two parts to be folded 16 and 17. In Figure 3 the direction rudder is shown with slits 18 and 19. Figure 4 shows the support 20 for the screw, marked with lines at which the said support is to 40 be folded. Figure 5 shows the screw 22.

The parts are cut out along the full lines and folded along the dotted lines.

45 As shown in these figures and in Figures 6, 7 and 8, the balance weight 23, occupying the place usually occupied by the motor, is formed by folding the two paper bands 10 and 11, which are preferably symmetrical with reference to the axis 50 of the toy aeroplane and are integral with the body or fuselage; the outer ends of the two bands form a tongue 24 which, after the folding, is inserted in the slit 4 cut in one of the bands.

The rear part of the body or fuselage, tapered 55 in imitation of a real aeroplane, is held in the

folded position by introducing the tongue 12 through the slit 5.

The direction controlling rudder is mounted in place by inserting the body or fuselage into the slit 18 until the end of the slit 18 abuts against the end of the slit 6a and the locking up of the assemblage is effected by inserting the tongue 13 through the slit 19 into the slit 6.

The wing piece of the monoplane, after folding on the lines 25 and 26, is inserted through 10 the slits 2, 3 which are of a length equal to the distance between the folds 25, 26 so as effectively to secure the wing piece at the front and at the back.

15 The teeth 14 and 15 are then bent out in the interior of the body to serve as filling pieces. The fold 17 which serves as an aileron or banking rudder is also bent into position. The part 16 alone remains folded at the leading edge and thus increases the rigidity of the wing and acts 20 as a securing member.

The lateral members of the body are thus supported on both sides, at the front and at the back, 25 interiorly by the teeth or filling pieces and exteriorly by the edge of the wing piece. Therefore also the wing piece cannot be displaced.

The curvature of the slits 2 and 3 gives the wing piece a cambered profile like that of actual aeroplane wings and this increases its rigidity. Moreover this mode of assembly brings into play 30 the resiliency of the body and of the wing piece, respectively, in two perpendicular planes and ensures great rigidity of the built up model.

The screw support 20 is introduced, after folding on the lines 21, into the interior of the balance 35 weight 23 and the screw is affixed by means of an ordinary dress pin.

The toy thus assembled and thrown into the air is capable of travelling correctly and gliding along a prolonged course. This valuable attainment is 40 conferred on the toy more especially by the arrangement of the balance weight with which it is provided near the front in the place where the motor is located in actual aeroplanes.

Moreover the toy responds to the inclinations 45 given to the direction and elevation rudders and to the ailerons or banking rudders. Its course can thus be varied at will.

In another constructional form, the toy can be 50 cut from a single piece of sheet material comprising the body or fuselage, the rear flight controlling members, the monoplane wings, the wheels and the balance weight.

In a further constructional form, the insertion 55 of the wing piece into the fuselage is effected at a

different height. As shown in Figures 9, 10, 11 and 12 the slits 27 and 28 are cut to form a wind screen 29 and the back 30 of the cockpit.

The wing piece, in this case also at a central part, comprises teeth 31, 32 which are introduced within the body or fuselage to act as filling pieces.

In this example it is unnecessary to provide folds to retain the wing piece in the slits. It can be introduced through the space between the wind screen and the back of the cockpit. The wing piece may be made with or without a front securing rib.

This method of attachment is also applicable in the case of a wing piece arranged in a lowered position, the slits in which it is inserted being then provided at the lower part of the body or fuselage.

In the case of machines with more than one motor, the wing piece can be cut in more than one piece each attached to the body or fuselage in the manner hereinabove described.

Figure 13 shows a toy biplane wherein this method of attachment is applied to both wing pieces 33 and 34. The lower plane 34 has an ex-tension forming a brace or stay 35 locked at its end in the upper plane 33 by means of a projecting tongue 36.

In a modification the support for the screw is omitted, and in place thereof there is provided a longitudinal extension of the lateral bands serving as the balance weight.

In the construction of a toy hydroplane with a hull or float, embodying the principle of this invention, a balance weight is provided forward of the hull and this not only adds to the equilibrium of the craft but also adds to the elegance of its silhouette.

It is to be understood that the cited examples are not to be taken as imposing any limitation, as the principle of the invention can be applied to any land or sea plane.

I claim:

1. Toy aeroplane constructed by cutting and folding sheets of paper or the like, comprising a fuselage of V section, a balance weight at the front part of the fuselage obtained by cutting and folding from the sheet, a wing inserted in the fuselage and a steering rudder attached to the fuselage.

2. Toy aeroplane constructed by cutting and folding sheets of paper or the like, comprising a fuselage of V section, means for spacing apart the members of the V section in the middle portion of the fuselage, means for keeping these members united in front and behind, a balance weight at the front part of the fuselage obtained by cutting and folding from the sheet, a wing inserted in the fuselage and a steering rudder attached to the fuselage.

3. Toy aeroplane constructed by cutting and folding sheets of paper or the like, comprising a fuselage of V section, means for spacing apart the members of the V section in the middle portion of the fuselage, means for keeping these members united in front and behind, bands integral with the front part of the fuselage and rolled and folded the said bands terminating in a point inserted, after folding, in a slit in the bands, an air screw constituted by folding paper or the like and inserted in the interior of the said folded bands, a wing inserted in the fuselage and a steering rudder attached to the fuselage.

4. Toy aeroplane constructed by cutting and folding sheets of paper or the like, comprising a fuselage of V section, means for spacing apart the members of the V section in the middle portion of the fuselage, means for keeping these members united in front and behind, a balance weight at the front part of the fuselage obtained by cutting and folding from the sheet, a wing inserted in the fuselage, a steering rudder attached to the fuselage, a direction controlling rudder, means on the direction controlling rudder and on the fuselage for securing these two elements together.

5. Toy aeroplane constructed by cutting and folding sheets of paper or the like, comprising a fuselage of V section, means for spacing apart the members of the V section in the middle portion of the fuselage, means for keeping these members united in front and behind, a balance weight at the front part of the fuselage obtained by cutting and folding from the sheet, slits in the fuselage which are cut to form the windscreens and the back of the cockpit, a wing inserted in the fuselage through the said slits and a steering rudder attached to the fuselage.

ETIENNE MARCUS.
